Ms. 135

U. S. Patent Office, of Geo. W. Chambers, Troy, N. Y.
Letters Patent No 235. Dated Oct. 9, 1859.

The schedule referred to in these Letters Patent and making part of the same.

To all whom it may concern:

Be it known that I, G. W. Chambers, of Troy, in the County of Rensselaer, and State of New York, have invented or produced a new design of parlor stove plate, which I call the "Clinton Parlor No. 24" and do hereby declare

309

that the following is a full clear and exact description of the same, reference being had to the accompanying drawing, making a part of this specification.

In the drawing I have represented only a part of the ornament, the remainder being a repetition of and corresponding with that represented on other parts of the plates, as is plainly to be seen by reference to the drawing.

What I claim as new and desire to secure by letters patent, is the design and configuration of an ornamental stove plate, as herein described, and represented in the annexed drawing.
